UNITED STATES PATENT OFFICE.

RANDOLPH SMITH, OF BALTIMORE, MARYLAND.

DISPENSING RECEPTACLE.

1,411,812.

Specification of Letters Patent. Patented Apr. 4, 1922.

Application filed August 23, 1921. Serial No. 494,573.

To all whom it may concern:

Be it known that RANDOLPH SMITH, a citizen of the United States, residing at Baltimore, in the State of Maryland, has invented certain new and useful Improvements in Dispensing Receptacles, of which the following is a specification.

This invention relates to improvements in dispensing receptacles and is particularly designed for use in connection with automobiles to supply water to the radiator although it may be used for other purposes where a fluid is to be supplied to a tank or receptacle through a filling nozzle.

15 In carrying out my invention I provide
a construction of receptacle that may read-
ily be hung from and supported by the
radiator nozzle so that the operator will
be relieved of the strain of holding the
20 receptacle in an awkward position during
the filling operation.

The invention is illustrated in the accompanying drawings, wherein,—

Fig. 1. shows the improved device in side elevation and attached to the filling nozzle of an automobile radiator.

Fig. 2. illustrates the same in top or plan view.

Fig. 3. shows the detached nozzle-engaging bracket in perspective.

Fig. 4. illustrates a sectional detail through the bracket,—the section being taken on the line 4—4 of Fig. 3.

Fig. 5. shows another sectional detail 35 through the bracket,—this section being taken on the line 5—5 of Fig. 3.

Fig. 6. illustrates the device in vertical sectional elevation and attached to the nozzle of a radiator,--the latter being viewed in front elevation.

Fig. 7. shows an inverted or bottom view of the detached receptacle as the same would appear if viewed on the line 7-7 of Fig. 6.

Fig. 8. shows an enlarged detail of one of the feet as the same would appear if viewed on the line 8-8 of Fig. 6, and

Fig. 9. illustrates a sectional detail through the valved discharge nozzle.

Referring to the drawing by reference characters the numeral 10 designates the receptacle proper which may have any desired outline shape, but which in this instance is rectangular in shape.

This receptacle by preference has its bottom 11, slightly elevated with respect to the lower edges of the vertical walls whereby

to form a bottom recess 12, for a purpose that will presently be explained, and as best seen in Figs. 6 and 7 of the drawings.

In order to distinguish one vertical wall 60 of the receptacle from another the front wall is designated 13; the rear wall 14 and the two side walls 15 respectively.

A cover 16 is preferably provided for the receptacle and may have a perforation 17 therein with a pivoted plate 18, adjacent thereto whereby said perforation may be covered, as shown in Figs. 2 and 6. 65

A bail or handle 19 is provided for the receptacle for convenience in lifting and carrying the same, and a ring or eye 20 is provided at one side and at the base of the handle whereby the receptacle may be hung on a wall if desired. 70

Suitable feet or supports 21, are attached to the bottom of the receptacle in the recess 12, and in this instance, the feet are formed of stiff wire with depending ends which are formed into a coil as shown in Fig. 8, and these coils are then covered with a rubber or other material 22, to prevent scratching the radiator when contacting therewith. 75 80

A bracket 23, is also secured to the bottom 11, of the receptacle and also in said recess 12, and this bracket extends forwardly from the front side or wall 13, and is slightly inclined at its forward end whereby it may embrace the nozzle 24, of a radiator 25, with as little contact as possible on the top face of the radiator itself. This embracing portion of the bracket is also covered with rubber or other material 26 to prevent scarring the enamel or paint. 85 90

Near the bottom 11, I provide an outlet opening 27 in the front wall 14 of the receptacle, and I preferably place a strainer 28 over said opening to prevent any foreign particles passing from the receptacle, if such should find their way therein. 10

A flexible hose 29, has one end attached at the outer side of the front wall over said discharge opening and the free end of this hose has a discharge nozzle 30 which may be inserted in the radiator nozzle 24 during 105 the filling operation.

I also prefer to provide a valve 31 in the hose-nozzle 30 whereby the flow of water or other fluid from the receptacle may be cut off at will, by operating a valve stem 32 that is attached to the valve and which extends through the hose nozzle.

To care for the hose when the device is not in use, I provide a clip 33, on the front wall 13, of the receptacle whereby the free end of the hose may be held in an elevated position against the front wall as indicated by broken lines in Fig. 1 of the drawing.

It is believed to be obvious that the receptacle may be hung by the bracket 26 engaging the nozzle 24 of the radiator while 10 the covered end of the feet 21, beneath the rear wall 14, will contact with the front wall of the radiator and thus hold the receptacle in place. The nozzle 30 will then be inserted in the nozzle 24 of the radiator and 15 the valve 31 when opened, will permit the water or other fluid to flow from the receptacle.

The feet serve as bracing means to rest against the vertical front of the radiator and 20 prevent the receptacle from swaying or lateral movement.

Having described my invention, I claim,—

1. A dispensing receptacle for attachment to automobiles the combination with a receptacle having a discharge outlet and means extending from the receptacle to engage a filling nozzle on the automobile to sustain the receptacle in the dispensing position.

2. A dispensing receptacle for attachment 30 to automobiles the combination with a receptacle having valved discharge means and means projecting from the receptacle to engage the automobile and sustain the receptacle in the dispensing position.

3. A dispensing receptacle for attachment to automobiles the combination with a receptacle having a discharge outlet, a movable tube extending from the outlet and means carried by and projecting from the

receptacle to engage the automobile and sustain the receptacle in dispensing position. 40

4. A dispensing receptacle for attachment to automobiles the combination with a receptacle having valved discharge means, means projecting from the receptacle to engage a filling nozzle on the automobile and means also projecting from the receptacle for bracing the latter while it is held in dispensing position. 45

5. A dispensing receptacle for attachment 50 to automobiles the combination with a receptacle having a discharge outlet, a flexible tube extending from said outlet, a bracket projecting from the receptacle to engage the filling nozzle of an automobile and means 55 also projecting from the receptacle to brace the latter and hold it against lateral movement while it is held in the dispensing position.

6. A dispensing receptacle for attachment 60 to automobiles the combination with a receptacle having a discharge outlet, a flexible tube extending from said outlet, a bracket projecting from the receptacle near the bottom of the latter and feet depending from 65 the receptacle and extending below the bracket.

7. The combination with a receptacle having a flat side and provided with an outlet near its bottom of a flexible tube leading 70 from said outlet, a valve device in said tube, means for holding the free end of the tube when the same is not in use and means projecting from the receptacle to engage an automobile part and sustain the receptacle 75 in dispensing position.

In testimony whereof I affix my signature.
RANDOLPH SMITH.
